Herbert R. Garside, ^{Inventor}
By his Attorney *J.B.M. Garside*

UNITED STATES PATENT OFFICE.

HERBERT E. GARSIDE, OF LONG ISLAND CITY, NEW YORK.

COUNTER FOR SHOES.

Application filed March 11, 1927. Serial No. 174,462.

My invention relates to shoes, and more particularly to the manner of shaping and applying the counter to the inner sole so that the shoe will at all times conform to the contour of the last about which its shape and size are to conform when finished.

One of the objects of my invention is to so shape the counter so as to cause it to fit the exact contour of the last at the top as well as at the bottom, without causing unnecessary work in the process of putting the counter on the shoe.

Another object of my invention is that the moulding of the counter to fit a particular shape and size last is accomplished without the extra work of taking care of the fullness that is ever present in the old style at the cone of the last, as well as causing the scarf edges of the counter to wrap around the bottom with the last.

My invention further consists in certain new and novel method of so shaping the counter as to cause it when applied to the last to lay close to the various curves of the same.

Prior to my invention, when the usual counter was applied to the last, by reason of the way it was shaped, it was impossible to get a uniform thickness of the same along the lines where the stitching goes. Again it required an extra degree of work by skilled workmen of the craft to get that part of the shoe when finished to look right. This not only consumed time to accomplish, but was expensive also, which are objectionable features, and which my present invention, among other things, serves to prevent. My improved shaped counter when applied to the shoe, will cause the shoe to present and maintain a very neat, shapely appearance, as will be more clearly understood from the following disclosure of a selected embodiment of my invention. This and other objects and features of the invention will be hereinafter described and pointed out, particularly in the appended claims.

My invention as at present preferred will be more clearly understood by reference to the drawing which illustrates the means for putting my invention into practice, and wherein,

Fig. 1 is a detached view of my improved counter before it undergoes its moulding process, showing in dotted lines the skived portions about its outer edges.

Fig. 2 is a section on the lines 2—2 of Fig. 1.

Fig. 3 is a partial view of the heel of a last showing my improved counter applied thereto, and

Fig. 4 is a rear end view of Fig. 3, showing the manner in which my improved counter hugs the curves of the last, before the scarf portions of the same are turned in.

In the construction of shoes of various styles, the counters are hidden by the inner lining, also by the outer covering of which the shoe may be composed, and its general lines and curves are moulded and worked upon by the shoemaker so as to get it to conform to the last. While to all appearances the usual counter fits the shoe, yet it in no way shows the amount of labor expended to get that result, nor does it show the manner, as such is covered by the coverings.

With my improved counter 10, skived all around as at 11, with its usual notch 12, and with its practically flat curve 13 and its greater curve 14, it will be seen from Fig. 3 how the counter 10 will fit about the heel of the last 15, and the lower skived edge or scarf 14 how it conforms to the curvature 16 of the last 15. The line of the last in the heel seat is straight and from there curves into the shank.

By curving the bottom of the counter 10, as shown at 14, it is possible to put the counter on in such a way as to make the parts fit the last perfectly, by the lay, or mould, of the counter as to make it fit tightly the last 15 as indicated in Fig. 4, and thereby obviate that fullness that is usual in the old style of counter. If in the lasting the counter does not fit close, then the counter and the shoe it is in are loose about the cone of the last, and do not fit the last perfectly, as before noted, therefore, it will not fit the foot.

As shown in Fig. 4 the scarf of the counter at the bottom is uniform throughout, and as shown in Fig. 3 the lines of the curve 14 fit the curved line of the last 15. By curving the lower line of the counter, the same may be fitted on the inner sole so that a uniform thickness of the counter lies opposite the sewing channel, with the result that the sewing seam 17 is uniform throughout. This cannot be so if the lower line of the counter is straight or practically so, as is now the custom to make them, as the stitching will go into the thicker part at some parts and the thin-

ner part in other. When the seam is not of a uniform thickness, the outside line of the shoe is irregular and the heel cannot be fitted on properly without extra time and labor.

5 To get the best results and appearance for shoes, the counter must be first of all cut the desired shape, and the final shaping of which is only accomplished after several manipulations, but when the lines of the counter are 10 as shown and described, the application and its results are appreciable by those in the trade, both from the time and labor saving as well as from the art lines it presents.

In accordance with the provisions of the 15 patent statutes, I have herein described and shown the preferred form of my invention which I now consider to represent the best embodiment thereof, but I desire to have it understood that to get the best results that it 20 is necessary to curve the scarf of the counter so as to have it conform to the last which it is formed for fit, thereby obviating any and all fullness at the cone of the last, which has been a continual source of annoyance to the trade.

What I claim and desire to secure by Letters Patent is:

1. A one-piece counter blank for shoes comprising a single piece of heavy material forming the body of the counter, all the edges of which are cut down or skived to be relatively thin, and decreasing in thickness toward the edge of the blank, and the top edge of the counter being relatively straight while the bottom edge is formed with joined curved portions, one of which is of greater degree of curvature than the other.

2. A counter blank for shoes comprising a body portion formed with a notch in its lower edge closer to one end of the body than to the other, the upper edge of the said body portion being practically straight, the portion of the lower edge to one side of said notch being slightly curved, and the portion of the lower edge on the other side of said notch being curved to a greater degree than the curve of the edge of the first portion.

In testimony whereof I affix my signature.
HERBERT R. GARSIDE.
